Primary Examiner — T Chase Nelson*Assistant Examiner* — Jeff Lenard D Torres(74) Attorney, Agent, or Firm — Banner & Witcoff, Ltd.CLAIM

The ornamental design for a shoe, as shown and described.

DESCRIPTION

FIG. 1 is a side photographic view of a shoe showing my new design;

FIG. 2 is a rear photographic view thereof;

FIG. 3 is an opposite side photographic view thereof; and,

FIG. 4 is a front perspective photographic view thereof.

The remainder of the shoe shown in a lighter grey photographic depiction forms no part of the claimed design.

1 Claim, 4 Drawing Sheets(56)
